CHAMPE GERALDINE FITZHUGH, OF WASHINGTON, DISTRICT OF COLUMBIA

CONTAINER

Application filed March 21, 1932. Serial No. 600,287.

This invention relates to containers, and more particularly to containers of the type used for viscous liquids such as edible oils.

Containers of the type heretofore used for liquids of this character, as, for example, vegetable oils commonly used in cooking, have been generally unsatisfactory, first, because of a lack of adequate pouring means which would permit the contents of the container to be poured easily and accurately, and without messing up the top of the container, which pouring means would also not interfere with the packing of containers for shipment, and secondly, because of a lack of proper facilities for protecting the contents against foreign matter, such as dust, after the container was initially opened.

It is therefore one of the objects of the present invention to provide a container of novel construction which embodies both improved pouring means and a protective cover for the pouring orifice, and which is easy and inexpensive of manufacture.

Another object is to provide a novel top for a container, made from an integral piece of material, which includes a pouring spout made integral with but being flexibly joined to the remainder of the top so that it may be bent either to a position where it overlies the top of the container in a substantially flat position, and hence does not interfere with the packing of containers for shipment, or to an outwardly extending position in which it may be used for pouring the contents from the container.

A further object is to provide a container top of new and improved construction wherein the portion in which is located the pouring orifice is punched upwardly or outwardly from the remainder of the top and is so located with respect to a pouring spout that the contents of the container may be poured easily and accurately without messing up the top surface of the container.

Still another object is to provide a container having a top of this novel construction with a removable cover member which may be placed over the pouring orifice so

as to protect it from foreign matter when it is not in use.

These and other objects will appear more fully from a consideration of the detailed description of the invention which follows. Although only one embodiment of the invention has been described and illustrated in the accompanying drawing, it will be understood that this drawing is for the purpose of illustration only, and is not to be construed as a limitation of the invention, reference being had for this purpose to the appended claims.

In the drawing, wherein like reference characters indicate like parts throughout the several views:

Fig. 1 is a perspective view of the upper portion of a container provided with a top embodying one form of the present invention, the protective cover member being shown lifted from its normal position;

Fig. 2 is a plan view of the container of Fig. 1 with the pouring spout bent inwardly into normal shipping or storage position; and

Fig. 3 is a sectional side view taken on line 3—3 of Fig. 2.

According to the embodiment of the invention shown in the drawing, a container, such as is commonly used for vegetable and other oils, comprises a substantially rectangular body portion 4 having a bottom portion (not shown) and to the upper edges of which is secured a top, indicated generally at 5, of a novel construction constituting one form of the present invention. The top 5 is preferably made out of a single integral piece of material, usually metal, stamped or otherwise formed into the shape disclosed.

As shown, top 5 comprises a substantially horizontal end wall portion 6 of substantially the same shape and size as body portion 4 of the container, around the periphery of which is formed an upstanding marginal portion 7 which may be of inverted U shape, and thus adapted to engage the upper edges of body portion 4 of the container and to be secured thereto in any suitable manner, as by crimping or soldering. When end wall portion 6 is thus secured to body portion 4

of the container, it forms a liquid-tight closure for the upper end thereof.

In order that the contents of the container may be easily poured therefrom, a part of end wall portion 6 closely adjacent any part of the periphery thereof is punched outwardly or upwardly so as to form an outwardly projecting portion 8, the upper surface of which is located in a plane slightly above the level of the top of upstanding marginal portion 7 of top 5. As shown, punched-out portion 8 is substantially rectangular in shape, but it will be understood that this shape may be varied as desired. In the upper surface of punched-out portion 8 closely adjacent to marginal portion 7 is provided a pouring orifice or outlet 9 and, if desired, a similar venting orifice 10 which is preferably located closer to the center of top 5 than pouring orifice 9.

Formed integrally with marginal portion 7 of top 5, at a point immediately adjacent punched-out portion 8 and pouring orifice 9, is a pouring spout portion 11 of any desired configuration. The section of material indicated at 12 in Fig. 3 is, if not naturally flexible, so treated as to become flexible so that spout portion 11 may be bent inwardly and outwardly about this section as a hinge or pivot, so as either to overlie punched-out portion 8, its normal shipping and storage position, or to extend outwardly at an angle thereto in pouring position. Pouring spout portion 11 is also preferably provided with side pieces 13 which are spaced sufficiently far apart that when said spout portion is bent inwardly these side pieces pass freely outside of and enclose the substantially vertical sides of punched-out portion 8.

In order to prevent dust and other foreign matter from entering the container or from gathering around pouring and venting orifices 9 and 10, especially after the container has first been opened, a removable cover member 14 has been provided which is of the same shape as punched-out portion 8 and the inner dimensions of which are such that it has a telescopic frictional fit with the substantially vertical sides of said punched-out portion. When placed in telescopic engagement with punched-out portion 8, cover member 14 provides an efficient air and liquid-tight closure for orifices 9 and 10 and effectively prevents any foreign matter from entering the container or gathering in and around orifices 9 and 10.

With this construction, when the container is filled at the factory, cover member 14 is placed over punched-out portion 8 and spout member 11 is bent inwardly to a substantially horizontal position overlying both punched-out portion 8 and its cover member 14, side pieces 13 passing outside of and enclosing the vertical sides of said member. In this position, containers may be

compactly packed for shipment and spout member 11 also serves to prevent accidental displacement of cover member 14. When it is desired to use the contents of the container, spout member 11 is bent outwardly to pouring position, as shown in Fig. 1, cover member 14 is removed, and the contents of the container are poured through orifice 9 onto the surface of spout member 11 and directed thereby in the manner desired. If all of the contents of the container are not removed therefrom initially, cover member 14 may be replaced to prevent contamination of the contents by foreign matter, and the container may be stored away with spout 11 either in its pouring position or in its inwardly bent position.

There is thus disclosed by the present invention a novel form of top for containers, particularly containers for liquids such as oils, which is highly economical of manufacture in that it may be formed from a single integral piece of material, and which is so constructed as to embody novel pouring means which render dispensing of the contents of the container a simple, efficient and clean operation. The portion of the container top in which the pouring orifice is located is punched outwardly from the remainder of the top and located closely adjacent a spout member which is flexibly, though integrally, connected to the upstanding marginal portion of the top by which the latter is secured to the body of the container. Also, a removable cover member has been provided for the punched-out portion in which the pouring orifice is located, which member protects the contents of the container against contamination by dust and other foreign matter.

It will be obvious that the invention is not limited to the exact structure shown in the drawing, but is capable of a variety of mechanical embodiments. For example, the shapes and locations of the punched-out portion and the spout portion of the top may be varied from those specifically disclosed. Various other changes, which will now appear to those skilled in the art, may be made in the form, details of construction and arrangement of the parts without departing from the spirit of the invention, and reference is therefore to be had to the appended claims for a definition of the limits of the invention.

What is claimed is:

1. An end closure for a container comprising an end wall portion adapted to close the end of the container, and outstanding marginal portion adapted for securement to the edges of the container sides, a punched-out portion adjacent said outstanding marginal portion raised above the level of said end wall portion and having a pouring orifice therein, and a spout portion flex-

ibly connected to said marginal portion adjacent the position of said punched-out portion and adapted to normally overlie said punched-up portion in a position substantially parallel with said end wall portion but to be bent to a position wherein it extends outwardly from said end wall portion at an angle thereto so as to form a pouring spout for the contents of said container 10 pourable through said orifice in the punched-out portion, all of said portions being formed out of an integral piece of material.

2. A top for a container comprising a substantially horizontal portion adapted to close the upper end of the container, an upstanding marginal portion adapted for securing said top to the body of the container, a punched-up portion having its upper surface substantially level with the top of said marginal portion and having a pouring orifice in said surface, and a spout portion flexibly connected with said marginal portion adjacent the location of said pouring orifice in 25 the punched-up portion and adapted for bending into either a position overlying said punched-up portion or a position extending outwardly at an angle thereto so as to form a pouring spout for the contents of said 30 container, all of said portions being formed from an integral piece of material.

3. A container having a top comprising a substantially horizontal portion adapted to close the end of the container, an upstanding marginal portion adapted for securing said top to the body of the container, a punched-up portion raised above the level of said horizontal portion and having a pouring orifice in its upper surface, a spout 35 portion flexibly connected with said marginal portion adjacent the location of said pouring orifice in the punched-up portion and adapted for bending into either a position overlying said punched-up portion or a position extending outwardly at an angle thereto so as to form a pouring spout for the contents of said container, all of said portions being formed from an integral piece of material, and a removable cover member 40 adapted to fit over said punched-up portion and thereby close said pouring orifice when not in use.

4. In a container, a top therefor comprising a substantially horizontal portion adapted to close the end of the container, an upstanding marginal portion of inverted U-shape adapted for securing said top to the body of the container, a punched-up portion raised above the level of said horizontal 45 portion and having a pouring orifice and a venting orifice in its upper surface, a spout portion flexibly connected with said marginal portion adjacent the location of said pouring orifice in the punched-up portion and adapted for bending into either a posi- 50

tion overlying said punched-up portion or a position extending outwardly at an angle thereto so as to form a pouring spout for the contents of said container, all of said portions being formed from an integral piece of material, and a removable cover member adapted for telescopic engagement with said punched-up portion for closing said pouring and venting orifices when not in use. 55

5. A container having a top formed from an integral piece of metal, said top having a punched-out portion adjacent the periphery thereof raised above the level of the rest of said top, a pouring orifice in said punched-out portion, and a pouring spout portion bendable with respect to the remainder of said top so as either to overlie said punched-out portion or to extend outwardly at an angle thereto so as to form a pouring spout for the contents of the container pourable through said orifice in the punched-out portion, and a removable cover member adapted to fit over said punched-out portion and thereby close said pouring 60 orifice when not in use. 85

In testimony whereof I have signed this specification.
